JOSEPH W. HOPKINS, OF BROOKLYN, (E. D.,) NEW YORK, ASSIGNOR TO HIMSELF AND CHARLES B. HARDICK, OF THE SAME PLACE.

Letters Patent No. 87,103, dated February 23, 1869.

IMPROVEMENT IN MACHINE FOR BRUSHING HATS.

The Schedule referred to in these Letters Patent and making part of the same.

To all whom it may concern:

Be it known that I, JOSEPH W. HOPKINS, of Brooklyn, (E. D.,) in the county of Kings, and State of New York, have invented and made a certain new and useful Improvement in Brushing, Finishing, or Polishing Hat-Bodies, and other articles; and I do hereby declare the following to be a full, clear, and exact description of the said invention, reference being had to the annexed drawing, making part of this specification, wherein—

Figure 1 is a vertical longitudinal section of my brushing or finishing-machine;

Figure 2 is a plan of the same; and

Figure 3 is an elevation of the gearing and mechanism for actuating finishing-brush.

Similar marks of reference denote the same parts.

In manufacturing hat-bodies, it is necessary to felt or full the cone, to give to it the necessary firm character. After this is done, the brushing-operation is performed on those hat-bodies that are to have a raised nap. This brushing-operation has heretofore been performed by hand, while the hat-body is wetted with hot water. This operation is slow, expensive, and very exhaustive to the operatives, the object of the brushing being to raise the nap, and smooth and polish the fibres on all sides.

My invention is primarily intended for brushing up the nap in hat-bodies, and consists in mechanism for giving the brush or polisher a motion corresponding to that by the human hand and arm, so that the brush or polisher can be revolved in a large or small ellipse, and in either direction, and supplied with water, so that the hat-body will be finished in the most perfect manner by the brushing and polishing.

In the drawing—

a is the bed of the machine, mounted on legs *b b*, and carrying the vat *c*, in which the hat-bodies are placed, and allowed to soak in hot water, and then removed, one at a time, to be operated on in the machine.

d is a bed, made for the reception of the article to be operated on.

This is mounted upon a vertical shaft, *e*, to which a treadle, *f*, is attached, so that the bed *d* and hat-body or other article thereon, can be pressed against the brush or polisher, as the same is moved, as hereafter indicated.

I have represented this bed *d* as made with a perforated surface, *2*, over a box, *3*, from which the water is led by a pipe, *4*, but this is only specially available where hot water is employed in brushing and finishing the hat-body and similar articles. This same device might be used in supplying steam below the article, while being brushed.

The brush or polisher *h* is at the end of an arm, *k*,

that slides through a movable fulcrum-stud, *l*, and connects to the crank-pin *i*.

This crank-pin *i* is movable in a slotted T-head, *m*, to the shaft *n*, so that the circle described by said crank-pin can be increased or lessened, and, by consequence, the movement of the brush or polisher *h* enlarged or diminished.

The shaft *n* is driven, from the shaft *p*, by the wheel *q* or *r* acting upon the wheel *s*. I prefer that these wheels be formed with bevel or mitre-faces, and there may be gear-teeth on said wheels, but usually the friction will be sufficient.

The springs *5 5* serve to keep the wheels *q r s* in contact. The wheels *q r*, however, are loose on the shaft *p*, and, according to which of said wheels *q* or *r* is coupled with the shaft *p*, by sliding the coupling *t*, by the lever *u*, so the crank-pin *i* will be revolved in either one direction or the other, by the shaft *n*, and move the brush *h* around in either one way or the other.

In order to vary the extent of motion given to the brush, and to render the same more or less elliptical, I adjust the fulcrum-stud *l* by the screw *v*, the elliptical movement being increased by moving the fulcrum *l* towards the shaft *n*, or lessened by the reverse movement.

The brush or polisher *h*, when used for finishing hat-bodies, is to be set into the bottom of a hollow box, *h'*, into which hot water is to be introduced by a flexible tube at *6*, the water passing out through small holes in the brush-block.

It will now be understood that the hat-body is to be laid on the bed *d* in a folded state, brushed on one side, turned over, brushed again, opened, refolded, and brushed on both sides, the folding being the same as when brushed by hand. The pressure can be regulated by the foot, leaving the hands at liberty in presenting the hat-body.

By this mechanism the cost of finishing, brushing, or polishing, is materially lessened, and the operations performed resemble those done by hand.

This mechanism might be applied to any other character of polishing and finishing that requires the peculiarity of motion set forth, but the same is especially adapted to brushing and finishing hat-bodies, where the fur requires to be brushed on one side, and then the motion reversed, to brush on the other side of the fibre, and, at the same time, a yielding pressure maintained of the brush upon the material.

What I claim, and desire to secure by Letters Patent, is—

1. The adjustable crank-pin *i*, arm *k*, fulcrum-stud *l*, and brush or polisher *h*, in combination with a bed, *d*, for the reception of the article to be operated upon, and mechanism for applying pressure upon the brush or polisher, substantially as set forth.

2. The adjustable fulcrum-stud *l*, in combination with the crank-pin *i* and brush or polisher *h*, for giving a greater or less elliptical movement to said brush or rubber, substantially as set forth.

3. The crank *i*, fulcrum *l*, arm *k*, and brush or rubber *h*, in combination with the gearing *q r s*, or its equivalent, for giving motion in either direction to the crank-pin *i*, for the purposes set forth.

4. A brush, applied to the bottom of a box for hold-

ing hot water, substantially as set forth, so as to keep the hat-body wet while being brushed or finished.

In witness whereof, I have hereunto set my signature, this 10th day of November, A. D. 1868.

JOSEPH W. HOPKINS.
